UNITED STATES PATENT OFFICE.

HARRY C. ZIMMERMAN, OF WASHINGTON, DISTRICT OF COLUMBIA.

CRANK AXLE FOR GUN CARRIAGES.

Application filed September 16, 1924. Serial No. 738,072.

(GRANTED UNDER THE ACT OF MARCH 3, 1883, 22 STAT. L. 625.)

The subject of this invention is a crank axle for gun carriages.

In artillery of small caliber of a type especially adapted to accompanying infantry troops on the advance or for use in mountainous country, the guns are portable structures, capable of rapid dismantling and assembly, and divisible into convenient individual loads.

10 The top carriage which supports the cradle and gun barrel is mounted directly on the carriage axle, the trails merely serving to lend stability in firing.

15 In the application of crank axles to this type of gun for the purpose of permitting angular adjustment of the carriage to secure increased range of elevation, it is evident that the top carriage must be removed when the axle is adjusted from low 20 angle to high angle position so that it may be mounted from the opposite side of the axle.

Furthermore, in effecting this adjustment the training mechanism which is normally 25 mounted on the rear side of the axle will be positioned on the forward side and hence inaccessible unless the wheels and axles are reversed. Provision must also be made in the axle to permit passage therethrough of 30 the elevating segment when the training mechanism is in either position of adjustment.

Inasmuch as revolvably supported trails are not feasible in a knock down gun of this 35 type and since they necessitate a more or less intricate locking device which must bear all the strain incident to firing when the axle is in high angle adjustment it is proposed to provide a reversible trail having 40 angular connections with the axle.

To these and other ends, my invention consists in the construction, arrangement, and combination of elements, described herein-after and pointed out in the claims forming 45 a part of this specification.

A practical embodiment of my invention is illustrated in the accompanying drawings, in which,

Fig. 1 is a view in side elevation of a gun 50 carriage with the rear side of the carriage cut away, showing the position of the axle when the carriage is mounted for low angle firing;

Fig. 2 is a similar view showing the carriage mounted for high angle firing;

Fig. 3 is a plan view of the axle;

Fig. 4 is a rear elevation of the axle;

Fig. 5 is an end elevation thereof;

Fig. 6 is a sectional view taken on the line 6—6 of Fig. 4 and showing the method 60 of attaching the trails;

Fig. 7 is a sectional view taken on the line 7—7 of Fig. 4; and

Fig. 8 is a sectional view taken on the line 8—8 of Fig. 4.

Referring to the drawings by numerals of reference:

The carriage comprises a pair of wheels 10 connected by a crank axle 11, which is preferably an I-beam formed with vertical 70 sockets open throughout, the central socket 12 adapted to receive the pintle of the top carriage 14 and the side sockets 13—13 positioned adjacent the crank arms and adapted to receive coupling bolts for locking parallel trails 15 to the axle.

Referring to Figure 6, the trail may be provided with forwardly extending apertured ears 16—16 adapted to be imposed on the axle by a sliding movement and held to 80 the axle in any suitable manner, as by means of a bolt 17 which may be removable from or retained in the socket 13 as shown, and as specifically claimed in a companion application Serial No. 738,074, filed September 16, 1924. The trails are connected at their rear ends by a symmetrical spade 18 adapted to anchor the carriage when mounted for either low or high angle fire as will appear more clearly hereinafter.

The central socket 12 is formed at either end with unequal bores forming seats having bushings 19 so that the pintle 20 of the top carriage 14 may be supported therein and inserted from either side of the axle. 95 The socket is formed with an exterior boss 21 for the reception and retention of a plunger 22 adapted to engage in a recess in the pintle for holding the top carriage to the axle.

The central socket includes upper and lower rectangular extensions 23 for the reception of brackets 24 designed to rotatably mount the training mechanism housing 25 from the axle.

The axle is formed with openings 26 at either side of the central socket to permit a pair of elevating segments 27 to pass through the axle and be removably secured to lugs 28 on the gun cradle. The segments are sup-

ported and guided in different sets of grooves formed in the housing 25 accordingly as the gun is mounted for low or high angle fire. It will be understood that when the cradle 5 is lifted from the segments they may be completely withdrawn from the axle and reinserted in the proper set of grooves in the housing.

Assuming the carriage to be positioned for low angle fire as shown in Figure 1, the adjustment for high angle fire is made by releasing the plunger 22 from the pintle and removing the top carriage and with it the cradle and gun. The trails are then uncoupled, the wheels swung about to position the training mechanism to the rear, the axle rotated 180°, and the trails turned over and again coupled to the axle. After removing the elevating segments to the opposite set 25 of grooves the cradle may be replaced by inserting the pintle of the top carriage in the central socket, the ends of the elevating segments being guided into the lugs on the cradle.

The necessity for turning over the trails is eliminated when removable coupling bolts are used and may also be obviated when using non-removable bolts by constructing the lower ear similar to the upper ear with a cut out portion 29 to slide past the oblong portion 30 of the bolt head when attaching the trail in either position of the axle.

While in the foregoing there has been illustrated and described such combination and arrangement of elements as constitute the preferred embodiment of my invention, it is nevertheless desired to emphasize the fact that interpretation of the invention should only be conclusive when made in the light of the subjoined claims.

I claim:

1. In combination with a pair of wheels, a crank axle on which the wheels are mounted, said axle formed with a plurality of vertical sockets, the central socket having symmetrical seats at opposite ends thereof adapted for the reception of a pintle from either side, rectangular extensions formed on said central socket to provide for attachment of a training mechanism, said axle further formed with apertures on either side of said central socket, trail members supported on said axle, and means passing through the trails and side sockets for locking the axle in position of adjustment.

2. In combination with a pair of wheels, a crank axle on which the wheels are mounted, said axle formed with a centrally disposed socket having symmetrical seats in opposite ends thereof, rectangular extensions formed on said socket to provide for attachment of

a training mechanism, said axle further formed with apertures on either side of said central socket, trail members supported on said axle, and means for holding the axle in 65 position of angular adjustment.

3. In combination with a pair of wheels, a crank axle on which the wheels are mounted, removable trail members supported on said axle, means for locking the axle and 70 trail together to hold the axle in position of angular adjustment, said axle formed with a symmetrical socket for supporting a top carriage in any position of adjustment, and said socket including rectangular extensions to 75 provide for attachment of a training mechanism.

4. In combination with a pair of wheels, a crank axle on which the wheels are mounted, removable trail members supported on said axle, means for locking the axle and trail together to hold the axle in position of angular adjustment, and said axle formed with a symmetrical socket for supporting a top carriage in any position of adjustment. 80

5. In combination with a pair of wheels, a crank axle on which the wheels are mounted, said axle adapted to support a removable top carriage and a fixed training mechanism, removable trail members supported on said 90 axle, and means for locking the trails to the axle to hold the axle in position of angular adjustment.

6. In combination with a pair of wheels, a crank axle on which the wheels are mounted, 95 said axle adapted to support a removable top carriage, removable trail members supported on said axle, and means for locking the trails to the axle to hold the axle in position of angular adjustment.

7. In combination with a pair of wheels, a crank axle on which the wheels are mounted, said axle adapted to support a fixed training mechanism, removable trail members supported on said axle, and means for locking the trails to the axle to hold the axle in 105 position of angular adjustment.

8. In combination with a pair of wheels, a crank axle on which the wheels are mounted, trail members having non-circular connecting members imposed on the axle, and means for locking the axle and trail together to hold the axle in position of angular adjustment. 110

9. In combination with a pair of wheels, a crank axle on which the wheels are mounted, removable trail members connected to the axle, and means for locking the axle and trails together to hold the axle in position of angular adjustment. 115

HARRY C. ZIMMERMAN.
